UNITED STATES PATENT OFFICE

WELINGTON A. ARNOLD AND EDWIN M. BABCOCK, OF MORAVIA, NEW YORK.

CARPET-STRETCHER.

SPECIFICATION forming part of Letters Patent No. 472,204, dated April 5, 1892.

Application filed March 21, 1891. Serial No. 385,897. (No model.)

To all whom it may concern:

Be it known that we, WELINGTON A. ARNOLD and EDWIN M. BABCOCK, of Moravia, in the county of Cayuga, in the State of New York, have invented new and useful Improvements in Carpet-Stretchers, of which the following, taken in connection with the accompanying drawings, is a full, clear, and exact description.

10 Our invention relates to carpet-stretchers, and particularly to that class in which a tack-driving mechanism is connected to the stretcher.

15 Our object is to produce an improved combined carpet stretcher and tacker which will stretch the carpet and at the same time carry the tack out of contact with the carpet, but in position for driving at the proper point by means of a vertical plunger.

20 Our invention consists in the several novel features of construction and operation hereinafter described, and which are specifically set forth in the claims hereunto annexed. It is constructed as follows, reference being had 25 to the accompanying drawings, in which—

Figure 1 is a side perspective of the machine complete with the handle broken off to reduce its length. Fig. 2 is a front elevation of same. Fig. 3 is a vertical sectional elevation on line $x-x$, Fig. 2, showing a tack in position ready for driving. Fig. 4 is a like view showing the plunger depressed and the tack driven.

25 A is the head-block, provided with a handle a , shown as consisting of a body and forked arms secured at their extremities to the block, and b is a tack-receiver suspended between said arms. The lower face of said block is provided with a series of teeth pointing forward, as shown. An opening is made vertically through said block, in which the plunger c is mounted, provided with a stop-collar d and projecting upward through the bracket e and having a flattened head, and f is a re- 30 turn-spring coiled around the plunger. A tack-tube h is inserted diagonally into the block, its lower end opening into the vertical opening, so that a tack placed in this tube will slide down and pass into position beneath 35 the plunger. A recess is cut in the front face of the block, in which we mount the frame m , having upturned ends, as shown, through

which the slide-rods n are passed provided with heads r , beveled on their inner faces, as shown, and having return-springs around the 55 rods, as shown, said heads being in vertical alignment with the plunger and across the bottom of the plunger-opening, so that the point of the tack coming beneath the plunger will be between said heads, and the tack will 60 be held upright thereby. Then when the carpet is stretched as desired the plunger is forced down, the tack is forced through between the heads, forcing them apart, and through the carpet and into the flooring, and 65 then when the pressure is removed the spring returns the plunger to its normal position, and the heads are again closed together by the spring behind them, ready for another 70 tack to be taken from the receiver and dropped into the diagonal tube or tack-conduit as before.

We are aware that prior to our invention combined carpet stretchers and tackers have been used in which tack-holding mechanism has 75 been applied to the hollow of a tube in which a hammer operates, and that a feeding-tube has been used in connection therewith, and we do not therefore desire to broadly claim such a construction; but

80 What we claim is—

1. A carpet-stretcher consisting of a head-block provided with teeth in its lower face and with a central vertical opening, a tube therein scarfed off on both sides at the bottom, a plunger in the tube, provided with a stop-collar, a head, and a retracting-spring between said head and collar, a tack-conduit tube inserted diagonally through the head-block and opening into the plunger-tube adjacent to its lower end, a frame having upturned ends inserted in a recess in the front lower edge of the head-block, bevel-headed bolts mounted horizontally in the ends of said frame and adapted to slide therein in opposite directions and normally meeting each other through the scarf-openings in the sides of the plunger-tube, springs operating to hold said bolts in meeting contact, and an operating-handle secured to the head-block, in combination, as set forth.

2. In a combined carpet stretcher and tacker, the combination, with a toothed head-block having a lateral recess in the face there-

of, of a perforated frame contained in the said recess and having vertical arms, and blocks having inclined adjoining facing sliding on the horizontal portion of the said frame on each side of the perforation therein, springs interposed between the said blocks and the vertical arm of the frame, a vertical tube within the said block registering with the perforation in the frame and having a double-scuffed lower end normally entirely closed by the faces of the said blocks, a plunger adapted

to be reciprocated within the said vertical tube, and an inclined tack-supplying tube connected with the said vertical tube, substantially as described. 15

In witness whereof we have hereunto set our hands this 18th day of March, 1891.

WELINGTON A. ARNOLD.
E. M. BABCOCK.

In presence of—
H. P. DENISON,
C. W. SMITH.
